(57) CLAIM

The ornamental design for a shoe, as shown and described.

DESCRIPTION

The patent or application file contains at least one drawing executed in color. Copies of this patent or patent application publication with color drawing(s) will be provided by the Office upon request and payment of the necessary fee.

1.1 is a front perspective view a shoe, showing my new design;

1.2 is a front view thereof;

1.3 is a back view thereof;

1.4 is a right-side view thereof;

1.5 is a left-side view thereof;

1.6 is a top view thereof; and

1.7 is a bottom view thereof.

2.1 is a front perspective view of a shoe, showing my new design;

2.2 is a front view thereof;

2.3 is a back view thereof;

2.4 is a right-side view thereof;

2.5 is a left-side view thereof;

2.6 is a top view thereof; and

2.7 is a bottom view thereof.

The characteristic features of the design lie in the shape of the shoe; protection for color of design no. 2 is claimed.

1 Claim, 14 Drawing Sheets
